US00D904458S

(12) **United States Design Patent** (10) Patent No.: **US D904,458 S**
(45) Date of Patent: ** Dec. 8, 2020

(54) **AUDIO INPUT/OUTPUT DEVICE**

(71) Applicant: **Amazon Technologies, Inc.**, Seattle, WA (US)

(72) Inventors: **Heinz-Dominik Langhammer**, San Francisco, CA (US); **Giles David Matthew McWilliam**, San Francisco, CA (US); **Marc Rene Walliser**, San Francisco, CA (US); **Christopher Green**, San Francisco, CA (US)

(73) Assignee: **Amazon Technologies, Inc.**, Seattle, WA (US)

(**) Term: **15 Years**

(21) Appl. No.: **29/636,845**

(22) Filed: **Feb. 12, 2018**

(57) **CLAIM**

The ornamental design for an audio input/output device, as shown and described.

DESCRIPTION

FIG. 1 is a first perspective view of an audio input/output device, taken from the front.

FIG. 2 is a second perspective view of the audio input/output device of FIG. 1, taken from the back.

FIG. 3 is a front view of the audio input/output device of FIG. 1.

FIG. 4 is a left-side view of the audio input/output device of FIG. 1.

FIG. 5 is a back view of the audio input/output device of FIG. 1.

FIG. 6 is a right-side view of the audio input/output device of FIG. 1.

FIG. 7 is a top view of the audio input/output device of FIG. 1; and,

FIG. 8 is a bottom view of the audio input/output device of FIG. 1.

The broken lines depict portions of the article that form no part of the claimed design.

1 Claim, 7 Drawing Sheets

Related U.S. Application Data

division of application No. 29/539,416, filed on Sep. 14, 2015, now Pat. No. Des. 781,918, which is a continuation-in-part of application No. 29/527,977, filed on May 22, 2015, now Pat. No. Des. 771,141.
